UNITED STATES PATENT OFFICE.

ALBERT KARRAS, OF HUDSON, WISCONSIN.

HIP-STRAP LOOP FOR HARNESS.

SPECIFICATION forming part of Letters Patent No. 298,589, dated May 13, 1884.

Application filed October 6, 1883. (No model.)

To all whom it may concern:

Be it known that I, ALBERT KARRAS, a citizen of the United States, and a resident of Hudson, in the county of St. Croix and State of Wisconsin, have invented certain new and useful Improvements in Hip-Strap Loops for Harness; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of so much of the back-strap and hip-strap of a set of harness as is sufficient to illustrate the application of my invention. Fig. 2 is a top view of the same. Fig. 3 is an end view. Fig. 4 is a top view of the metallic lining for the hip-strap; 20 and Figs. 5 and 6 are sectional views on lines *x x* and *y y*, Fig. 2.

Similar letters of reference indicate corresponding parts in all the figures.

My invention has relation to metallic linings for loops in the back-strap of a set of harness, through which the hip-strap passes; and it consists in the improved construction and combination of parts of such a lining, which will prevent the hip-strap from wearing the loop in the back-strap out, and will stiffen the back-strap at that point, as herein-after more fully described and claimed.

In the accompanying drawings, the letter A indicates the back-strap, which consists of two layers of leather—an upper layer, B, and a lower layer, C—which are stitched together, excepting at the point where the hip-strap passes through the back-strap.

D is a metallic lining, having a transverse flat perforation, E, through which the hip-strap may pass, and having upwardly-projecting flanges F at the upper sides of the ends of the said perforation, and provided with two longitudinal extensions or wings, G, extending from the sides of the perforated lining or plate.

This lining or plate is inserted between the two layers of the back-strap, and the edges of the layers are stitched together upon the sides of the wings or extensions, holding them fast, while the flanges at the ends of the transverse perforation prevent the upper layer of the strap from becoming displaced from the upper side of the lining, the said layer fitting between the said flanges. The hip-strap H passes through the perforation, and it will be seen that the metallic lining will prevent the latter from drawing the loop formed by the two layers of the back-strap out of shape or from wearing it out; and it will likewise be seen that the lining and its wings will serve to stiffen the back-strap at that place, preventing the hip-strap from cutting too much into the rump of the horse, if the ends of the hip-strap should be drawn down by the traces or by other connected parts of the harness.

Having thus described my invention, I claim and desire to secure by Letters Patent of the United States—

1. A lining for the loop for the hip-strap in the back-strap in harness, consisting of a plate having a transverse perforation, upwardly-projecting flanges at the ends of the said perforation, and longitudinal wings or extensions, as and for the purpose shown and set forth.

2. The combination of the back-strap, consisting of two layers stitched together at their edges and forming a loop, a lining consisting of a plate having a transverse perforation, upwardly-projecting flanges at the ends of the perforation, and longitudinal wings or extensions, and a hip-strap passing through the perforation in the lining, as and for the purpose shown and set forth.

In testimony that I claim the foregoing as my own I have hereunto affixed my signature in presence of two witnesses.

ALBERT KARRAS.

Witnesses:

THOMAS F. MOSS,
JAMES WESTEN.
